CONVERTIBLE ELEVATOR FOR TRUCKS

Glenn Simons, Larabee, Iowa

Application July 22, 1944, Serial No. 546,163

2 Claims. (Cl. 214—83)

My invention pertains to an elevator which can be attached to standard trucks.

An object of my invention is to provide an elevator which is pivoted to one side of a truck body, and which can be carried in inoperative position substantially parallel to the truck body and which can then be placed in substantially vertical position for operation.

A further object of my invention is to provide an elevator which can be used to empty the truck box of grain and elevate the same, and then discharge the grain into bins adjacent to the truck.

A further object of my invention is to provide such an elevator which can also be used for filling the truck box with grain.

A further object of my invention is to provide an interchangeable arrangement which will allow the same elevator to perform both of the above mentioned functions of discharging the truck of grain and of filling the same.

A further object of my invention is to provide a device which can be powered from the power take-off of the truck.

A further object of my invention is to provide an elevator which can be filled at the bottom thereof and which will then convey the grain upwardly and into the truck box.

A further object of my invention is to provide detachable parts to perform the above functions, which detachable parts will not be in the way when the elevator is not used.

A further object of my invention is to provide the above mentioned objects in a simple construction requiring very little space and very little weight.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation of the truck with the elevator attached.

Figure 2 is a sectional view taken substantially along the lines 2—2 of Figure 1.

Figure 3 is a detail of the driving arrangement for driving the elevator, and taken substantially along the lines 3—3 of Figure 5.

Figure 4 is a detail of an upper end of the elevator.

Figure 5 is a detail taken along the lines 5—5 of Figure 2, and

Figure 6 is a section taken along the lines 6—6

of Figure 5 with the exception that the closure plate is attached instead of the filling tube.

My invention contemplates the provision of a small elevator unit which can be attached to a truck which will greatly simplify the operation of emptying the truck or filling the same, eliminating the use of a great deal of manual labor otherwise necessary.

I have used the character 10 to designate one side of a truck box, character 11 the other side, and character 13, the base. The box is carried on the usual supports 13 which comprise the framework of the truck, the hood of which is indicated by the character 14, the forward wheels 15 by the character 15, and the rearward wheels by the character 16, and the cab by the character 17. Pivottally attached to the side 10 of the truck is the elevator enclosure 18 which is rectangular in shape and of substantial height, which is attached to the substantial pin 19 which is received in a suitable boss 20 and which pin 19 is secured at 21, and which construction allows pivoting of the entire elevator casing 18.

Suitably journaled at the upper end of the casing 18 is the shaft 22 which is attached to the centrally arranged sprocket 23 over which passes the chain 24. Attached to the chain 24 are a series of small cup-shaped buckets 25 used for elevating the grain. Communicating with the upper end of the casing 18 is the substantially horizontal portion 26 which terminates in the downwardly extending neck 27 which is received within the portion 28 of the discharge spout 29. The connection at 28 permits the discharge spout to be positioned outwardly of the truck, as shown in Figure 2 by the solid lines, or inwardly toward the truck box, as shown by the dotted lines.

Journaled at the lower end of the elevator casing 18 is the further shaft 30 to which is attached the centrally arranged sprocket 31 over which passes the aforesaid belt 24. The casing 18 includes the lower expanded portion 31 which portion 31 receives an indented door 32 which includes the handle 33, the door 32 being snugly engaged with the perimetral outwardly extending flanges 34, the door 32 including the sides 35 to provide a snug engagement with the flanges 34. The shaft 30 terminates in the outer square portion 36 which is received within the square socket 37 which is attached to the small shaft 38 which shaft, in turn, is attached to a universal joint 39 which joint is attached to the shaft 40. Attached at 41 at the upper end of the shaft 40 is the universal joint 42 which is also attached to the small stub shaft 44. A remov-

able pin 43 passes through the socket 37 and the portion 36. The shaft 44 includes the collar 45, and the shaft 44 is supported by means of the bearing 46 which is attached to the bracket 47 which is supported from the base of the box. Attached at the end of the shaft 44 is the bevel gear 48 which meshes with the further bevel gear 49 which bevel gear is attached to the power take-off shaft 50 of the truck.

Slidably engaged above the truck base 12 is a rod 51 which includes the handle 52 and the stop member 53. The rod 51 is attached to a plate 54. Positioned substantially centrally of the truck box is the opening 55 which communicates with a substantially arcuate tapering funnel 56 which is attached at 57 to the base 12. Hinged at 58 to the funnel 56 is a further elongated tapering funnel or tube 59 which terminates in the flange 60 at the lower end thereof, and the tube 59 communicates with the portion 31 of the elevator through the opening 61. Arranged about the opening 61 are a series of studs 62 and the flange 60 includes suitable openings for receiving the studs 62 upon which studs are screwed the nuts 63 for attaching the lower end of the tube 59 to the elevator. The shaft 30 can be journaled outwardly on an extending bracket 64 or any other construction can be used.

Pivoted secured at 65 is the U-shaped member 66 having the outwardly projecting prongs so that when it is desired to retain the conveyor or elevator member 18 in vertical position, the prongs are pivoted outwardly to the position shown in Figure 2, thereby retaining the elevator in fixed position. Similarly, a further U-shaped member 67 is pivoted at 68 (see Figure 1) to the side 10 of the truck box so that when the elevator 18 is swung to the horizontal position, or when it is not in use, the U-shaped member 67 can be swung outwardly in the same manner to retain the elevator in horizontal position. The U-shaped members are frictionally engaged with the pivoting points so that they will remain in fixed position.

The operation of the arrangement is as follows. As explained above, when the truck is traveling, the elevator is in the horizontal position and is completely out of the way. Also, when the truck is transporting grain, etc., the tube 59 is pulled upwardly by pivoting it at the hinge 58 and can be attached to a small hook at 69 so that it will not project downwardly and will be completely out of the way. When it is desired to empty the truck box, the elevator is brought to the vertical position after the bracket 67 is released therefrom, and the bracket 66 is brought to the outwardly extending position. A plate 70 which is used to cover the opening 61 is then removed by removing the nuts 63 from the studs 62. The flange 60 which is an integral part of the tube 59 is then placed with the openings therein over the studs 62, and the tube 59, after being swung down to the filling position as shown by the solid lines in Figure 2, is then attached to the opening 61 in this manner, and the nuts 63 are again screwed onto the studs.

The elevator is driven by means of the shaft 46, and when the shaft 40 is not in use it can be swung upwardly with the lower socket 27 hooked to an accessible place at the bottom of the truck similar to the arrangement shown wherein the tube 59 is used thereto. The universal joint at 42 will allow such attachment, and when the shaft is to be used, it is swung down carrying the joint 39 and the small shaft and

socket 38 and 37; the socket 37 is then placed over the squared end 36 and the pin 43 is passed through these members. This forms the driving arrangement, since the power take-off bevel gear 49 drives the further bevel gear 48 which, through the shaft 40, the universal joints 39 and 42, and the socket 37, will drive the shaft 30. Next, the handle 52 which is attached to the rod 51 is pulled outwardly until the stop member 53 strikes adjacently to the wall 11, which brings the plate 54 beyond the opening 55 which communicates with the funnel 56 and the tube 59, leaving the opening 55 unrestricted.

During driving of the power arrangement the grain will then gravitate centrally through the tube into the lower housing 31 and will then be conveyed upwardly by the buckets 25 and into the portion 26 and the spout 29 and thence outwardly into the receiving bin which is positioned adjacently to the truck. The spout 29, during this operation, of course, is positioned outwardly as shown by the solid lines in Figure 2 and as explained heretofore. In those cases where it is desired to fill the truck box with grain, the tube 59 is left in the upper supported position, and the rod 51 is placed in normal position, and the spout 29 is turned about the neck 21 so that it points inwardly toward the box. The aforesaid plate 70 is then attached to the opening 61 or is left remaining in this position, and the door 32 is removed by means of the handle 33. The grain is then shoveled or fed from a bin into the expanded opening 31 directly into the lower end of the conveyor, so that the grain will be elevated and deposited into the truck box. After use, the pin 43 can be removed and the shaft 40 and the shaft 38 can be pivoted upwardly and attached as explained heretofore, to an outer lower portion of the truck. After this operation the entire conveyor 18 can be swung to horizontal position and out of the way. The truck can then be driven to any point for delivering or picking up grain as explained, with a relatively light and small elevator attached thereto ready to perform the necessary operations.

It will now be seen that I have provided an elevator for trucks which is pivoted to one side of a truck body and which can perform all of the operations as mentioned in the objects of my invention, and it will be seen further that I have provided other advantages readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In combination with a truck box, an elevating conveyor pivotally attached to one side of the box, means for pivoting said conveyor to vertical position, means communicating from the bottom of said box to the bottom of said conveyor to transfer material from said box thereto, including a lower funnel tube, said box having an opening communicating with said tube, means for driving said elevator from the truck power-take-off, means for selectively filling said truck box including an outer door attached at the lower end of said conveyor, opening of said door providing means for depositing material therein and conveying such material upwardly, the upper end of said conveyor including a reversible spout attached thereto for conveying grain inwardly

into said box, a slidable member slidably engaged with the base of said truck box adapted to open said opening when moved outwardly.

2. In combination with a truck box, an elevating conveyor pivotally attached to one side of the box, means for pivoting said conveyor to vertical position, means communicating from the bottom of said box to the bottom of said con-

veyor to transfer material from said box thereto, including a lower funnel tube, said box having an opening communicating with said tube, said lower funnel tube including a lower hinged portion, means for supporting said hinged portion in upper position.

GLENN SIMONS.
